UNITED STATES PATENT OFFICE.

WILLIAM A. SMITH AND CLARENCE H. DOCKHAM, OF DETROIT, MICHIGAN, AS
SIGNORS TO CHICAGO PNEUMATIC TOOL COMPANY, OF NEW YORK, N. Y., A COR-
PORATION OF NEW JERSEY.

PNEUMATIC TOOL.

Application filed May 2, 1921. Serial No. 466,189.

To all whom it may concern:

Be it known that we, WILLIAM A. SMITH and CLARENCE H. DOCKHAM, both citizens of the United States of America, residing at 5 Detroit, in the county of Wayne and State of Michigan, have invented certain new and useful Improvements in Pneumatic Tools, of which the following is a specification, reference being had therein to the accompanying drawings.

The invention relates to percussive tools of that type in which a free flying piston is controlled in its movements by a valve alternatively admitting fluid under pressure 15 on opposite sides thereof. The invention has more particular reference to the construction of the controlling valve and the means for operating the same as more fully hereinafter set forth.

20 In the drawings:

Figure 1 is a longitudinal section through the tool and valve, showing the piston at one end of its stroke, and a valve set for returning the same;

25 Figure 2 is a similar view with the piston at the completion of its return stroke and the valve set for again driving the piston forward;

Figure 3 is a view similar to Figures 1 and 2 showing a modified construction of valve;

Figure 4 is a similar view showing still another modification of the valve;

Figures 5 and 6 are views similar to Figures 1 and 2 showing another modification;

Figure 7 is a section on line 7-7 of Fig. 5;

Figure 8 is an end elevation of the valve. 40 A is the main cylinder for containing the free flying piston B and which is provided with a central annular exhaust passage C communicating with the exhaust port D. The piston B is provided with a shank E fitting an extension F of the cylinder of reduced diameter and the end of this shank is adapted to impinge against the tool G mounted in said extension.

45 The valve H occupies a cylinder I at one side of the main cylinder A and comprises essentially end head portions H' and H'', a central head or disk H³ and intermediate grooves or annular chambers H⁴ and H⁵ forming the main air feeding passages.

Surrounding the valve within the cylinder I 55 are bushings J and J' and centrally between said bushings is formed an annular port K controlled by the disk H³ to be placed alternately in communication with the grooves H⁴ and H⁵.

The shifting of the valve is controlled by the conjoint action of leak ports establishing communication from the main air supply to the opposite ends of the valve cylinder I, and exhaust ports leading from said opposite ends of the valve cylinder to the main cylinder at points intermediate the annular exhaust passage and the end of the cylinder. These exhaust ports are therefore sealed by the piston before it has reached 70 the end of its stroke, which permits the building up of pressure in the end of the valve cylinder to shift the valve. As shown, L and L' are the leak passages which are formed respectively in the bushings J and 75 J' and extend from the main air channel to the ends of the valve cylinder. These passages are sufficiently restricted so that when the valve cylinder is in communication with the exhaust, the pressure in said cylinder is 80 not materially raised by the leakage. On the other hand, whenever the exhaust connection to the valve cylinder is cut off, the pressure within said cylinder will rapidly rise. M and M' are the exhaust passages 85 leading from the opposite ends of the valve cylinder to the main cylinder and, as shown, the ports N and N' opening into the main cylinder are located upon opposite sides of the annular exhaust channel C and a considerable distance from the end of the cylinder. The valve cylinder I is further provided with exhaust ports O and O' which are controlled by the heads H' and H³ of the valve. These ports communicate with 90 annular channels P and P' in the bushings J and J', the arrangement being such that when the valve is at the end of the cylinder adjacent to one of said channels, the latter will be in open communication with the annular air channel in said valve, so that any pressure within said channel and the main cylinder in communication therewith may be exhausted. These channels also 95 intercept any leakage past the heads H' and H³ from one side to the other thereof. R and R' are passages extending from the opposite ends of the main cylinder to the

valve cylinder at points intermediate the heads H' , H^2 and the disk H^3 .

With the construction as thus far described, in operation, the pressure fluid, such as compressed air, entering through the channel Q will be in communication through the annular port K with one or the other of the valve channels H^4 and H^5 , according to the position of the valve. As shown in Figure 1, the piston B is in a position at the end of its forward stroke and the valve H is shifted to the right-hand end of the valve cylinder, so that communication is established from the channel Q through the port K, channel H^4 and passage R to the left-hand end of the cylinder A. This pressure is therefore operating to return the piston, while the opposite end of the cylinder is in free communication with the exhaust channel C.

The movement of the piston in its return stroke closes the exhaust channel C and then the port N' of the exhaust passage M' from the valve cylinder, which permits the building up of pressure at the right-hand end of said valve cylinder. After the piston has over-ridden the port N and the exhaust channel C, the pressure in the chamber on the left-hand end of said piston will be exhausted and also the pressure on the left-hand end of the valve. This permits the built up pressure at the right-hand end of the valve cylinder to quickly shift the valve, cutting off communication between the annular port K and channel H^4 and establishing communication between said port and passage H^5 , the parts being in the position shown in Figure 2. The high pressure fluid is therefore admitted to the main cylinder at the right-hand end thereof, while at the same time the annular port P is placed in communication with the channel H^4 so that in the forward stroke of the piston the fluid on the left-hand side thereof can be exhausted through the port O.

In the construction shown in Figure 3 the valve heads H' , H^2 and disk H^3 are of equal diameters which equalizes the pressure areas on said disk and on the inner faces of the heads H' and H^2 . I prefer, however, a construction in which the area of the disk is somewhat in excess of that of the end heads and as shown in Figures 1 and 2, the disk is of slightly greater diameter and slides in a portion S of enlarged diameter in the bushings J and J' . Thus the pressure of the fluid within the channels H^4 and H^5 which is exerted oppositely upon the end heads and the central disk, has a differential tending to hold the valve in position without regard to the pressure which is exerted on the end of the valve.

In the modified construction shown in Figure 4 the central disk H^3 , instead of forming peripheral contact with the cylinder

seats upon the end of the bushings J and J' operating as a poppet valve. The construction is otherwise the same as Figures 1, 2 and 3.

In the construction shown in Figures 5 to 8 the leak passages are formed in the valve, instead of being in the bushings. Thus, as indicated in Figure 7, the center disk H^3 has the cross passages T therein which communicate with axial passages T' through restricted ports T^2 . This will permit a constant leakage of air from the main supply passage Q to the opposite ends of the valve cylinder, which will cause the valve to operate as before described.

The double exhaust for the piston chamber is provided in order that any leakage of air past the valve disk H^3 after the main exhaust channel C has been covered by the piston at the beginning of its stroke, due to a worn valve, will be taken care of by the auxiliary exhaust ports O and O'. The auxiliary exhaust ports also perform the function of providing a vent to atmosphere for the small amount of air passing from the restricted leak passages L and L' into the cylinder through the ports M N or M' N'. It will be thus apparent that by providing the auxiliary exhaust ports O and O' excessive compression in the ends of the cylinder is avoided and that the period of such compression on each stroke is delayed to the latest possible moment thereby making possible a very free acting piston with a minimum of back pressure.

What we claim as our invention is:

1. In a fluid pressure operated tool, a cylinder, a piston reciprocable therein, said cylinder having a main exhaust port overrun by said piston, motive fluid inlet passages opening into said cylinder adjacent the ends thereof, a valve controlling the movements of said piston and arranged to admit motive fluid in alternation to said passages, means for shifting said valve in timed relation with the movements of said piston including a passage supplying motive fluid continuously in limited amount to one pressure area of said valve, a valve controlling exhaust passage extending from said area to said cylinder intermediate said main exhaust port and one end of said cylinder, and auxiliary exhaust means controlled by said valve for said end of the cylinder whereby the full stroke of the piston is secured and any tendency of the valve to shift prior to the closing of said valve controlling exhaust passage by said piston is avoided.

2. In a fluid pressure operated tool, a cylinder, a piston reciprocable therein, said cylinder having a main exhaust port overrun by said piston, motive fluid inlet passages opening into said cylinder adjacent the ends thereof, a valve controlling the movements of said piston and arranged to

- admit motive fluid in alternation to said passages, said valve having opposed pressure areas, passages admitting motive fluid continuously in limited amount to said areas, 5 valve controlling exhaust passages from said areas opening into said cylinder on opposite sides of said main exhaust port and between the latter and said motive fluid inlet passages, and an auxiliary exhaust for one 10 end of said cylinder under control of said valve for insuring a full stroke of the piston toward said end and for avoiding any tendency of the valve to shift prior to the closing of the valve controlling exhaust passage 15 at said end of the cylinder by the piston.
3. In a fluid pressure operated tool, a cylinder, a piston reciprocable therein, said cylinder having a main exhaust port over-run by said piston, motive fluid inlet passages opening into said cylinder adjacent the ends thereof, a valve controlling the movements of said piston and arranged to admit motive fluid in alternation to said passages, said valve having opposed pressure areas, 20 passages admitting motive fluid continuously in limited amount to said areas, valve controlling exhaust passages from said areas opening into said cylinder on opposite sides of said main exhaust port and between the latter and said motive fluid inlet passages, and auxiliary exhaust means for both ends 25 of said cylinder under control of said valve in alternation with the admission of motive fluid to said ends for insuring full strokes 30 of said piston in both directions and for avoiding any tendency of the valve to shift until the respective valve controlling exhaust ports are closed by the piston.
4. In a fluid pressure operated tool, a cylinder, a piston reciprocable therein, said cylinder having a main exhaust port over-run by said piston and passages opening into said cylinder adjacent the ends thereof, a valve controlling the movement of said piston and arranged alternately to effect communication of said passages with the motive fluid inlet and with an auxiliary exhaust, said valve having opposed pressure areas, 40 passages admitting motive fluid continuously in limited amount to said areas, and valve controlling exhaust passages from said areas opening into said cylinder on opposite sides of said main exhaust port and intermediate the latter and said first named passages 45 thereby to insure delay in the shifting of said valve near the end of each stroke of the piston until after the respective valve controlling exhaust passage is closed by the piston.
5. The combination of a piston, a valve 50 having end heads, a central disk and chambers between said heads and disk, a casing including a cylinder having a main exhaust port over-run by said piston, a cylindrical casing for said valve having a main fluid
- supply port alternately communicating with the chambers of said valve in different positions of adjustment thereof, leak passages extending from the main air passage to chambers at opposite ends of said valve, 70 exhaust passages extending respectively from the opposite ends of said valve casing to said cylinder at points on opposite sides of said main exhaust passage and intermediate the same and the ends of the cylinder, 75 passages in communication with the chambers of said valve extending to opposite ends of the cylinder, and auxiliary exhaust ports alternatively in communication with said chambers of the valve. 80
6. The combination of a piston, a valve having end heads and a central disk of larger diameter with chambers intermediate said disk and said heads, a casing including a cylinder having a main exhaust port over-run by said piston, a valve casing having a main air port controlled by said central disk to be placed in alternative communication with said valve chambers, passages respectively communicating with said chambers 90 and leading to the opposite ends of said cylinder, fluid leak passages extending to chambers at opposite ends of said valve, passages extending from said end chambers to said cylinder on opposite sides of said main 95 exhaust passage and intermediate the same and the ends of the cylinder, and annular grooves surrounding said end heads and provided with exhaust ports, said grooves being alternatively placed in communication with the chambers of said valve and intercepting leakage from the ends of the valve to said chambers. 100
7. The combination of a piston, a cylinder having an exhaust port over-run by said piston, a valve for controlling the movements of said piston, a leak passage for continuously admitting motive fluid in limited amount to a pressure area of said valve, and a valve-controlling exhaust passage for said pressure area communicating with said cylinder at a point intermediate the main exhaust thereof and one end of the cylinder thereby to effect shifting of the valve by built up pressure when said valve-controlling exhaust passage is closed by said piston and to relieve said pressure through said cylinder exhaust when the piston uncovers said valve controlling exhaust passage and overruns said exhaust port. 110 115
8. The combination of a piston, a valve controlling the movements of said piston, a casing forming a cylinder for said piston and also housing said valve, said cylinder being provided with a main exhaust port over-run by said piston, auxiliary exhaust means controlled by said valve for one end of said cylinder, and valve-controlling exhaust ports communicating with said cylinder on opposite sides of said main exhaust port and re- 120 125 130

spectively sealed by said piston at opposite ends of its stroke, and motive fluid leak passages for building up opposing pressures on said valve respectively on the sealing of the 5 corresponding valve-controlling exhaust ports.

9. The combination of a piston, a valve controlling the movement of said piston, a casing forming a cylinder for said piston 10 and also a housing for said valve, said cylinder having a main exhaust port over-run by said piston, auxiliary exhaust means controlled by said valve for both ends of said cylinder, and a pair of valve-controlling exhaust ports communicating with the cylinder 15 on opposite sides of said main exhaust port and between the same and the opposite ends of the cylinder, said valve-controlling exhaust ports being respectively sealed by the 20 piston when at the opposite ends of its stroke, and motive fluid leak passages for building up opposing pressures on said valve when the respective controlling exhaust ports are sealed.

25 10. The combination of a piston, a valve having end heads of equal diameter and a

central head or disk of larger diameter with chambers intermediate said disk and head, a casing including a cylinder having a main exhaust port over-run by said piston, a valve 30 cylinder having a main air port controlled by said central disk to be placed in alternative communication with said valve chambers, passages respectively communicating with said valve chambers and leading to the 35 opposite ends of said cylinder, fluid leak passages extending to chambers at the opposite ends of said valve, and passages extending from said end chambers to said cylinder on opposite sides of said main exhaust passage 40 and intermediate the same and the ends of the cylinder, said passages being alternately sealed by said piston to cause the building up of pressure in the connecting chamber at the end of the valve for shifting the same, 45 and the differential area of said central disk in excess of said end head tending to hold said valve in shifted position.

In testimony whereof we affix our signatures.

WILLIAM A. SMITH.
CLARENCE H. DOCKHAM.
